BALL-WINDING MACHINE

John R. Gammeter, Akron, Ohio

Application March 17, 1945, Serial No. 583,215

21 Claims. (Cl. 242—3)

1

This invention relates to machines for applying thread rubber, cord or other continuous flexible material, and in particular relates to ball winding machines.

An object of the invention is to provide improved means in a ball or like winding machine, whereby when the flexible material being wound onto a ball or core is broken, or when the normal continuity of the material is otherwise interrupted, operation of the machine will be automatically stopped to prevent snarling of the material.

Another object of the invention is to provide a ball-winding machine having improved means for automatically stopping operation of the machine when a ball thereon has been wound to predetermined size.

Other objects of the invention will be manifest from the following brief description and the accompanying drawings.

Of the accompanying drawings:

Figure 1 is a front elevation, partly broken away, of a ball-winding machine embodying the features of the invention.

Figure 2 is a top plan view of Figure 1.

Figure 2a is a fragmentary plan view, partly broken away, taken at the lower left hand corner of Figure 2.

Figure 3 is a fragmentary end elevation, viewed substantially at 3—3 in Figure 2.

Figure 4 is a fragmentary end elevation, viewed substantially at 4—4 in Figure 2.

Figure 5 is a fragmentary cross-section, greatly enlarged, taken substantially on line 5—5 of Figure 1, illustrating the winder or feed mechanism.

Figure 6 is a rear elevation, partly broken away, of the mechanism shown in Figure 5.

Figure 7 is a front elevation, partly broken away, of the mechanism shown in Figure 5.

Figure 8 is a fragmentary view taken substantially at 8—8 in Figure 7.

Figure 9 is a schematic wiring diagram of the electrical equipment embodied in the invention.

Referring particularly to Figures 1 and 2, there is shown a golf-ball winding machine of conventional type, similar to the machine disclosed in applicant's prior Patent No. 647,256, issued April 10, 1900, with reference to the principle utilized for winding thread rubber onto a ball core. According to this winding principle a ball core C is yieldingly retained between two pairs of spaced rollers 10, 10 and 11, 11 rotatably mounted in spaced holder members 12 and 13, the pairs of rollers being arranged with the respective axes thereof in vertical planes parallel to a vertical

2

winding plane through the center of core C, and the holder members being carried by supports 14 and 15 mounted as shown to be simultaneously and uniformly separable against the yielding action of springs 16, 16, to permit growth of core C as thread rubber R, for example, is wound thereon by a rotating winder or material feed mechanism, indicated generally at W. Intermittent gear mechanisms, indicated generally at 17, are provided in casings 17a, 17a for rotating the rollers in various directions, whereby a compound rolling action is imparted to the ball which will result in constantly changing great circles of the core C being presented to said winding plane. This compound rolling action of the core C with respect to the winding plane results in uniformly spherical growth of the winding.

For the purpose of the present invention gearing in casings 17 is driven by a shaft 18, which 20 in turn is adapted to be driven by a belt 19 shiftable from an idler pulley 20 on said shaft to a driver pulley 21 keyed thereon. To this end, the belt 19 is manually shiftable at will between pulleys 20 and 21, by means of a belt-shifting yoke 25 pivoted at 23a intermediate the ends of an elongated lever 24, which is pivoted at one end thereof to a top supporting plate 25 of the machine, as indicated at 26. The other end of lever 24 extends freely forwardly of the machine to 30 provide an operating handle therefor.

The lever 24 is normally yieldingly retained in the inoperative position thereof shown in Figure 2. For this purpose a bar 27 is pivotally connected at one end to lever 24 at 23a and extends 35 laterally on the under-side of plate 25, the other end of the bar having thereon an off-set lug 28 to which a rod 29 is connected to be slidably received through a recess in a bracket 30, secured to said plate, so that a compression spring 31 40 received on rod 29, between the bracket and said lug, will tend to urge bar 27 to the left (Figure 2) as limited by engagement of an adjustable stop nut 30a on the end of rod 29 against bracket 25a.

The lever 24 may be releasably retained in an 45 operative position thereof, in which belt 19 drives pulley 21, as previously described, by means of an electrically operated latch mechanism 33 of known type, secured to the under-side of top plate 25. Accordingly, there is provided a hooked portion 34 on the end of bar 27, adjacent rod 29, adapted to engage over a shiftable catch 33a of the latch mechanism, when lever 24 is urged to the right against spring 31 (Figure 2), thereby 50 to maintain the machine in operation until the mechanism is again released. The latch mecha-

nism may be releasable at will by an operator momentarily pressing a button 34a to close an electrical circuit, to withdraw catch 33a, and thereby permit spring 31 to urge lever 24 to the left and stop the machine. Said electrical circuit is indicated in the wiring diagram in Figure 9 by lines 35 and 36 connecting lines L₁ and L₂ from a suitable source of electrical supply. Other electrical connections to this latching device will be described later.

The winder or rotatable feed mechanism W, for applying the material R to a core C is primarily a ring 38 which is mounted to rotate about an annular track member 39 fixedly supported on top plate 25. The track 39 comprises an inner bearing ring 39a and a radially outwardly extending annular flange 39b threaded thereon, and is arranged so that the ring 38 will rotate concentrically around a core C in holders 12 and 13. Ring 28 is adapted to be rotated by meshing engagement of external gear teeth 40 thereon with a gear 41, which is driven, through bevel gears at 42, by the shaft 18 being driven as previously described. That is, the rollers 10 and 11 of the holder members, and the winder ring 38 are operated as described, simultaneously, by shaft 18 being driven through manual operation of lever 24 to the right to shift yoke 23 to move belt 19 from idler pulley 20 onto driver pulley 21.

Upon operation of releasing mechanism 33 to stop the machine as set forth above, it is desirable that ring 38 will not continue rotating due to momentum thereof, as such continued rotation would minimize effectiveness of safety automatic control means to be described later. To this end a brake 45 is pivotally connected at 46 to the machine frame to be yieldingly urged, by a tension spring 46a, into frictional engagement with pulley 21 when lever 24 is released to inoperative position. A suitable cam 47 on bar 27 is adapted to engage an upwardly projecting flange 48 on the brake to release the same, against the action of spring 46a, when lever 24 is operated to start the machine (see Figure 2a). By means of a handle 49 the brake 45 is releasable to permit rotation of the winder W for operational adjustment or setting purposes.

Referring particularly to Figures 5 to 8, there is shown a reel-supporting bracket 51 which is secured to ring 38 to rotate therewith. This bracket is provided with spaced lugs 52 and 53 which are apertured to receive a removable pin 54, which may be locked against relative rotation in said apertures by means of a spring-pressed detent 55. The pin is quickly removable and insertable, from one side of the bracket, for rotatably receiving thereon a spool or reel 56 of thread-rubber or similar flexible material R. Adjustable tension means is provided at 57 by which yielding pressure is applied through a tension member 58 yieldingly to engage one end of reel 56.

Indicated generally at 60 is guide means for directing the continuous thread rubber R from reel 56 to the ball-winding plane, previously referred to, this guide means being carried by rotatable winder ring 38. In guide means 60 there is provided a rod 61, supported between lugs 52 and 53 of bracket 51, around which the thread rubber from reel 56 may be guided to clear the inner periphery of track 39 and to extend rearwardly thereof to be engaged around an annularly grooved roller 62, which is carried by arm 63 secured to a radially inward extension 64 of said bracket (see Figures 5 to 7). From roller 62 the thread rubber is trained to extend for-

wardly of the machine to engage around a concave roller 65 mounted on said bracket extension 64, the material then being guided rearwardly and radially inwardly in said winding plane by means of a roller 66, also secured to said extension 64. A guide needle 67, of known type, is pivoted at 68 to bracket extension 64 with a bifurcated or slotted free end thereof extending to be relatively close to a ball or core C retained between the holder members 12 and 13, so that the material R passed through said bifurcated end will be maintained in said winding plane. This arrangement is such that when the machine is operated as previously described, to rotate the ring 38 simultaneously with operation of said holder members to impart compound rolling movement to core C, the thread material will be wound on the core in constantly changing great circles. The tension of the material R, as applied to the ball or core C, is adjusted by means of the adjusting device 57 (see Figure 7).

Should the material R for any reason become broken, means is provided for automatically stopping the machine so that the fault can be corrected. To this end, pivotally mounted at 70 on the extension 64 of bracket 51 may be an arm 71, of electro-conductive material, which is adapted to extend substantially in the direction of a chord of the inner periphery of an annular track member 39a and to engage under the two of the reaches formed by the material R extending rearwardly and forwardly in a loop about roller 62. Thus in normal operation of the machine one or both of said reaches of material R engaging arm 71 will prevent radially outward swinging movement thereof, due to centrifugal force, when the ring 38 is rotated. The arm 71 may have an extension 71a on the side of pivot 70 opposite thereto, to act as a counter-balance for efficient operation. Fixedly secured on electrical insulators 72 on fixed track member 39b may be a contact ring 73 of electro-conductive material, said ring being arranged concentric with ring 38 and with its inner edge in line with arm 71 (see Figure 5), whereby upon release of the arm 71 by disengagement with the material R, as described (see Figures 5 and 6) the arm will be swung radially outwardly by centrifugal force as the winder ring 38 is rotated, to make an electrical connection with contact ring 73. For the latter purpose the arm 71 and ring 73 may be connected in an electrical circuit, in parallel with the previously described circuit through switch button 34, to the releasable latch 33 (see Figure 9). Accordingly the arm 71 is connected through line 75 to power line L₂, and ring 73 is connected by line 76 through latching device 33 to power line L₁, to complete the circuit. Thus if the material R is broken during the operation of the machine for winding a ball, arm 71 upon engaging ring 73 will close the circuit through lines 75 and 76 and latching device 33, thereby releasing bar 27 which is yieldingly urged by spring 31 to move lever 24 to its previously described inoperative position.

As only a momentary contact between arm 71 and ring 73 is required to release bar 27, means is provided to open the last described electrical circuit when the machine is stopped. To accomplish this, a spring-pressed switch 77 may be provided to have an operating pin 78 thereon engageable by lever 24 when it moves into said inoperative position, thereby to maintain switch 77 in open condition when the machine is not in operation (see Figures 2 and 9). Conversely,

when lever 24 is operated to start the machine switch 77 will close to set the circuit through lines 75 and 76 in condition for subsequent use as previously described when the thread material again becomes broken.

Means may also be provided automatically to stop the machine when a ball wound therein has grown to predetermined spherical size. This is accomplished by provision of an arm 79 (see Figure 2) extending from one holder support 14, at the side of the center line of the machine opposite to a pivotal point 14a of the support. Yieldingly and adjustably mounted on top plate 25 may be a switch 81 having an operating pin 82 which is engageable by said arm 79 upon the ball growing to said predetermined size, thereby to close an electrical circuit (see Figure 9), through a line 83 connecting power line L₂, and a line 84 connecting power line L₁ through the releasable latching device 33. The last named circuit is connected through latching device 33 in parallelism with the two previously described circuits therethrough. To obviate maintaining a closed circuit through line 83 and 84 when the machine is not in operation, a spring-pressed switch 85 has an operating pin 86 engageable by lever 24 upon latching device 33 being released, in the manner previously described with reference to switch 77.

For operation of the machine for winding golf balls, for example, continuous thread rubber or like continuous flexible material is first fed from reel 56 around guide rod 61, around rollers 62 and 65 to form a loop having closely adjacent reaches extending rearwardly and forwardly through track member 39a, and from roller 65 the material is guided around the roller 66, and through the slot of needle 67 and onto a core C of known type, said material thereby being guided to the core in a winding plane which extends through the center of said core. The free end of the material is passed around the core C several times to secure it thereto prior to operation of the machine.

Next, the operator manually urges lever 24 to the right, as viewed in Figure 2, to engage hooked extension 34 of bar 27 with catch 33a of the electrical latching device 33. The catch 33a will retain lever 24 in the operative position until latching device 33 is subsequently actuated to release hook 34 through the action compression spring 31. This operation of lever 24, through yoke 23, will move the belt 19 from the idler pulley 20 to driven pulley 21 and shaft 18, thereby to cause compound rolling movement of core C held between the holder members simultaneously with rotation of ring 38 about track 39a. The rotary movement of ring 38, carrying the feed or winder mechanism W and guide means 60 therewith, is effective to wind the thread material R under desired tension in constantly changing great circles about core C to desired uniform wall thickness, as previously described. Should it be desirable for any reason to stop the machine, as for example, for the purpose of making adjustments, the operator may do so by pressing button 34a (Figures 2 and 9) to release latching device 33 to stop the machine. The machine will similarly be stopped, automatically, upon the ball being wound to desired size causing operation of holders 12 and 13 to move the arm 79 to predetermined position to release the latching device 33 through operation of switch 81.

Should normal operation of the machine be interrupted by a break in the material R, or by

substantial slackening of the same, the arm 79 will be released to contact the ring 73 in any position of rotation of winder ring 38, which will close the wiring circuit through lines 75 and 76 to operate latching device 33, and thereby automatically stop the machine.

Thus has been provided an improved ball or like winding machine having means incorporated therein whereby it will be automatically stopped immediately either upon the ball having grown to predetermined size, or upon an interruption in the continuous feeding of the thread material to the core C. Obviously, the machine is adapted to be used for winding or applying materials other than thread rubber, such as cord, steel wire, steel tape, fibre glass or other continuous flexible material. Also, the invention is not limited to use for winding golf-balls but may be utilized for winding the materials mentioned to form or reinforce other articles, such as baseballs, hollow athletic balls, tubular articles, etc. It will be understood from certain characteristics of golf balls, pertaining particularly to standard diameters, weights, balance, resiliency upon impact with a golf club head, etc., that golf ball manufacturing procedures must necessarily be exacting to provide uniformity in production. This uniformity, of course, is materially affected by any deviation from feeding the thread material through the machine under requisite normal tension. The expression "interruption in the normal continuous winding of said material," for example, as contemplated in the claims, therefore, presupposes any condition which will interrupt the continuous normal feeding of the thread material to the ball being wound in the machine, such as a break in the material, or a slackening thereof, or exhaustion of the supply of material.

Modifications of the invention may be resorted to without departing from the spirit thereof or the scope of the appended claims.

What is claimed is:

1. The combination in a machine for winding continuous flexible material to form an article, of a holder for said article, a feed mechanism mounted to rotate about said holder, means rotatable with said feed mechanism for guiding continuous material from the same to said holder to wind the material on an article supported thereon, an element normally supported by a portion of said continuous material, and control means operated by said element for maintaining the machine in operative condition by the element being so supported, interruption in the continuity of said material thereby rendering the machine inoperative.

2. The combination in a machine for applying continuous material to form a ball or other article, of a holder for said article, a support, a winder mounted on said support to rotate about said holder, means for guiding continuous material from said winder to an article being wound on said holder, a relatively fixed contact element mounted in association with said winder, a shiftable contact element mounted to be relatively rotatable with said winder and having a portion engageable with a stretch of said continuous material normally to hold said element out of electrical contact with said fixed contact element, said shiftable contact element being engageable with said fixed contact element upon failure of said stretch of material to support said portion of the shiftable contact element, and electrical control means connected to said con-

tact elements and operable therethrough to control operation of the machine.

3. The combination in a machine for applying continuous material to form a ball or other article, of a holder for said article, a support, a winder mounted on said support to rotate about said holder, means for guiding continuous material from said winder to an article being wound on said holder, a control means electrically operated to control operation of the machine, a relatively fixed contact element mounted in association with said winder, and a shiftable contact element mounted to be relatively rotatable with said winder and having a portion engageable with a stretch of said continuous material to maintain said control means in one condition of operation of the machine and release of said shiftable contact element by said stretch of continuous material setting said control means in another condition of operation.

4. The combination in a machine for applying continuous material to form a ball or other article, of a holder for said article, a support, a winder mounted on said support to rotate about said holder, means for guiding continuous material from said winder to an article being wound on said holder, a control means electrically operated to control operation of the machine, a relatively fixed contact element mounted in association with said winder, and a shiftable contact element mounted to be relatively rotatable with said winder and having a portion engageable with a stretch of said continuous material to maintain said control means in one condition of operation of the machine and release of said shiftable contact element by said stretch of continuous material setting said control means in another condition of operation, said fixed contact element comprising an electro-conductive ring, and said shiftable contact element comprising an electro-conductive part shiftable upon being released to engage said ring.

5. The combination in a ball or like article-winding machine of a holder for an article, a support, a winder mounted on said support to rotate about said holder, means for guiding continuous material from said winder to an article being wound on said holder, control means electrically operated to control the operation of the machine, a relatively fixed ring of electro-conductive material mounted in association with said support, and an electro-conductive element shiftable mounted in association with said winder and rotatable therewith, said shiftable element being normally held out of contact with said ring by engagement thereof with said continuous material, said ring and shiftable element being electrically connected to said control means for controlling the operation of the machine.

6. The combination in a ball or like article-winding machine of a holder for an article, a support, a winder mounted on said support to rotate about said holder, means for guiding continuous material from said winder to an article being wound on said holder, control means electrically operated to control the operation of the machine, a relatively fixed ring of electro-conductive material mounted in association with said support, and an electro-conductive element shiftable mounted in association with said winder and rotatable therewith, said shiftable element being normally held out of contact with said ring by engagement thereof with said continuous material, said ring and shiftable element being electrically connected to said control means

for controlling the operation of the machine, said shiftable element being pivoted to swing outwardly into contact with said ring by centrifugal force when released by said continuous material.

5 7. The combination in a ball or like article-winding machine of a holder for an article, a support, a winder mounted on said support to rotate about said holder, means for guiding continuous material from said winder to an article being wound on said holder, control means electrically operated to control the operation of the machine, a relatively fixed ring of electro-conductive material mounted in association with said support, and an electro-conductive element comprising a pivoted arm engageable by the reaches of said loop normally to hold the arm out of contact with said ring, said pivoted arm being swingable outwardly into contact with said ring by centrifugal force when released by said continuous material, said ring and shiftable element being electrically connected to said control means for controlling the operation of the machine.

10 8. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition to rotate the winder, and means operable by an abnormal condition in said continuous material to release said releasable means to render said power means inoperative.

15 9. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition to rotate the winder, means operable by an abnormal condition in said continuous material to release said releasable means to render said power means inoperative, said holder including relatively shiftable members between which the article is held and the members being shiftable by growth of the article as said material is wound thereon, and means operable by said relative shifting of said members to release said releasable means when the windings have attained a predetermined size.

20 10. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition to rotate the winder, means operable by an abnormal condition in said continuous material to release said releasable means to render said power means inoperative, and means operable by release of said releasable means for stopping rotation of said winder when the power means is stopped.

25 11. The combination in a machine for applying continuous material to form a ball or other article,

of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, a mechanism actuated by an abnormal condition in said continuous material to release said electrical device, means operable by growth of the article wound on said holder to predetermined size to release said electrical device, and means operable by release of said releasable means to prevent operation of said electrical device.

12. The combination in a machine for applying continuous material to form a ball or other article, of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, means operable by growth of the article wound on said holder to predetermined size to release said electrical device, and means operable by release of said releasable means to prevent operation of said electrical device.

13. The combination in a machine for applying continuous material to form a ball or other article, of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, a mechanism actuated by an abnormal condition in said continuous material to release said electrical device, and means operable by release of said releasable means to prevent operation of said electrical device.

14. The combination in a machine for applying continuous material to form a ball or other article, of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, a mechanism actuated by an abnormal condition in said continuous material to release said electrical device, and means operable by growth of the article wound on said holder to predetermined size to release said electrical device.

15. The combination in a machine for applying continuous material to form a ball or other article, of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, and means operable by growth of the article wound on said holder to predetermined size to release said electrical device.

16. The combination in a machine for applying continuous material to form a ball or other arti-

cle, of a holder for said article, a support, a winder mounted on said support to rotate about said holder, means for guiding continuous material from said winder to said holder, power means for rotating said winder, releasable means manually operable to set said power means in operative condition to rotate the winder, an electrical device operable to release said releasable means, and a mechanism actuated by an abnormal condition in said continuous material to release said electrical device.

17. The combination in a machine for winding continuous flexible material, of means for guiding and continuously feeding the material in the machine, power means for maintaining the machine for continuous feeding of the material, an electrically operated control device for starting and stopping said power means, a relatively fixed electro-conductive element, a relatively movable electro-conductive element mounted to move into electrical contact with said fixed element but being normally restrained by a reach of said continuously fed material to be held out of such electrical contact with the fixed element, an electrical circuit connecting said fixed and movable elements to said control device, interruption in the normal continuity in the feeding of said material thereby releasing said movable element to contact said fixed element and through said circuit to operate said control device and thereby through said power means to render said machine inactive.

18. The combination in a machine for winding continuous flexible material to form a ball or other article, of means for guiding and continuously feeding the material in the machine, power means for maintaining the machine for continuous feeding of the material, an electrical control device for said power means and including means manually operable to control the power means, a relatively fixed electro-conductive element, a relatively movable electro-conductive element mounted to be engageable with said fixed element but normally supported by a reach of said continuously fed material to be out of engagement with the fixed element, an electrical circuit connecting said fixed and movable elements to said control device, interruption in the normal continuity of said material thereby releasing said movable element to contact said fixed element and through said electrical circuit to operate said control device and thereby through said power means to render said machine inoperative, electrical means operable by growth of the article formed in the machine to predetermined size, a second electrical circuit connecting said electrical means in parallel with said first-named circuit to said control device for independently operating the control device to render the machine inoperative, and means in electrical connection with said first-named and second parallel circuits adapted to open and close the circuits upon operation of said control device for inoperative and operative conditions of the power means respectively, whereby the machine is not operable unless said manually operable means is operated for starting said power means.

19. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition

to rotate the winder, said holder including relatively shiftable members between which the article is held and the members being shiftable apart by growth of the article as said material is wound thereon, and electro-responsive means operable by said relative shifting apart of said members to release said releasable means, and means for mounting said members to be relatively shiftable, said mounting means including an arm which swings one of said members about a fixed pivot at one side of the same, said pivoted arm having an extension thereof from the other side of its member, and said electro-responsive means including an electrical switch having an operating part engageable by said arm extension upon growth of said article to predetermined size.

20. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition to rotate the winder, said holder including relatively shiftable members between which the article is held and the members being shiftable apart by growth of the article as said material is wound thereon, and electro-responsive means operable by said relative shifting apart of said members to release said releasable means, and means for mounting said members to be relatively shiftable, said mounting means including an arm which swings one of said members about a fixed pivot at one side of the same, said pivoted arm having an extension thereof from the other side

of its member, said electro-responsive means including an electrical switch having an operating part engageable by said arm extension upon growth of said article to predetermined size, and means being provided for mounting said switch in yieldingly fixed position relative to said arm extension.

21. The combination in a machine for applying continuous material to form a ball or other article, of a holder for said article, a support, a winder mounted on said support to rotate about said holder, means for guiding continuous material from said winder to said holder, power means for rotating said winder, releasable means for maintaining said power means in operative condition to rotate the winder, said holder including relatively shiftable members between which the article is held and the members being shiftable apart by growth of the article as said material is wound thereon, and electro-responsive means operable by said relative shifting apart of said members to release said releasable means, and means for mounting said members to be relatively shiftable, said mounting means including an arm which swings one of said members about a fixed pivot at one side of the same, said pivoted arm having an extension thereof from the other side of its member, said electro-responsive means including an electrical switch having an operating part engageable by said arm extension upon growth of said article to predetermined size, and adjustable means being provided for mounting said switch in yieldingly fixed position relative to said arm extension.
